UNITED STATES PATENT OFFICE.

HARLEY E. RUTTER, OF PITTSBURGH, PENNSYLVANIA.

WRENCH.

1,424,521.

Specification of Letters Patent. Patented Aug. 1, 1922.

Application filed September 24, 1921. Serial No. 502,971.

To all whom it may concern:

Be it known that I, HARLEY E. RUTTER, a citizen of the United States, and resident of Pittsburgh, in the county of Allegheny and 5 State of Pennsylvania, have invented a new and useful Improvement in Wrenches; and I do hereby declare the following to be a full, clear, and exact description thereof.

My invention relates to improvements in 10 wrenches, and more particularly to that type of wrenches in which there is a stationary jaw and a movable jaw engaging a guide in said stationary jaw, and a handle pivotally mounted on the stationary jaw and connected to the movable jaw, whereby upon moving said handle the movable jaw is moved toward and from said stationary jaw.

The object of my invention is to simplify 20 in many respects the construction of such wrenches, and provide means whereby the movable jaw may be readily detached and a new one secured in place without the necessity of taking the wrench all apart.

To these ends my invention comprises the 25 novel features hereinafter set forth and claimed.

In the accompanying drawing Fig. 1 is a vertical elevation of my improved wrench with the jaws open; Fig. 2 is a like view with 30 the handle partly broken away and the jaws in section; Fig. 3 is an edge view showing the stop-plate removed for withdrawing the movable jaw to the position indicated in dotted lines, Fig. 2; Fig. 4 is an opposite edge view; Fig. 5 is a view showing the 35 movable jaw removed; and Fig. 6 is a vertical sectional view of the fixed jaw removed.

In the drawing the numeral 2 designates a suitable handle which is pivoted by the 40 bolt 3 to the bifurcated portion 4 of the stationary jaw 5.

The stationary jaw 5 has the guideway 6 formed therein with the shoulders 7 adapted to receive the extension 8 of the movable 45 jaw 9.

A link 10 is connected by the pin 11 to the extreme upper end of the handle 2, and the opposite end of said link is connected by the screw 12 to the lug 13 on the movable jaw 9.

50 In order to control the outward move-

ment of the movable jaw 9, a stop-plate 14 is provided which is secured in place by screws 15 entering openings 16 in the ends of the fixed jaw 5.

When my improved wrench is in use and 55 it is desired to grasp the pipe 16, or other object, the handle 2 is moved to the position indicated in full lines, Fig. 2, which acts to pull the movable jaw 9 so as to engage the pipe 16 and clamp it securely between the 60 jaws.

In case it is desired to remove the movable jaw 9 it is only necessary to remove the 65 screws 16 and withdraw the plate 14, whereupon by moving the handle 2 to the position indicated in dotted lines in said figure, the screw 12 which connects the link 10 to the lug 13 of the movable jaw 9 is exposed to view, and by unscrewing said screw said movable jaw is released and a new one can 70 be applied, or the old jaw may be repaired and restored again to place. This is made possible by having the link 10 pivoted to the outer end of the movable jaw 9.

By my invention I provide a very efficient 75 and simple form of a wrench of this particular type in which there is a direct pull upon the movable jaw when brought into engagement with the object to be operated on, while at the same time the removal of 80 the movable jaw is conveniently provided for without taking the wrench entirely apart.

What I claim is:

1. In a wrench, the combination of a member carrying a stationary jaw and having a guideway, a movable jaw having an extension engaging said guideway, a handle pivotally connected to said member, a link pivotally connected to the upper end of said 90 handle and to a lug formed at the outer lower end of said movable jaw, and a removable stop plate secured to said member for limiting the movement of said movable jaw away from said fixed jaw. 95

2. In a wrench, the combination of a member carrying a stationary jaw and having a guideway, a movable jaw having an extension engaging said guideway, a handle pivotally connected to said member and having 100

a straight extension above its point of pivotal connection, a link pivotally connected to the upper end of said handle and to a lug formed at the outer end of said movable jaw, said link being so proportioned that said link and said handle form substantially a right angle when said jaws are open to their maximum extent, and a removable stop plate secured to said member for limiting the move-

ment of said movable jaw away from said fixed jaw.

In testimony whereof, I, the said HARLEY E. RUTTER, have hereunto set my hand.

HARLEY E. RUTTER.

Witnesses:

JOHN F. WILL,
EDITH K. FREESE.
